UNITED STATES PATENT OFFICE.

WILLIAM A. FEARN, OF COLUMBUS, OHIO.

DESIGN FOR A SASH-RIBBON BUCKLE.

SPECIFICATION forming part of Design No. 23,032, dated February 6, 1894.

Application filed January 4, 1894. Serial No. 495,709. Term of patent 7 years.

To all whom it may concern:

Be it known that I, WILLIAM A. FEARN, a citizen of the United States, residing at Columbus, in the county of Franklin and State 5 of Ohio, have invented and produced a new and original Design for Sash-Ribbon Buckles; and I do hereby declare the following to be a full, clear, and exact description of the same, reference being had to the accompanying 10 drawings, forming a part thereof.

In the drawings referred to, Figure 1 is a side view of my design of sash ribbon buckle; and Fig. 2 is an edge view.

As shown in the views, the buckle consists 15 of a substantially rectangular frame having side portions 1 and 1, the bars 2 extending between said side portions forming rectangu-

lar slots, and a rounded lower part 3 having a circular hole 4. The side bars 1 and 1 opposite the lowest slot are slightly curved or 20 expanded so that the frame is of slightly greater width at this point than in the lower rounded part 3.

What I claim, and desire to secure by Letters Patent, is—

The design for sash ribbon buckles substantially as described and shown.

In testimony whereof I affix my signature in presence of two witnesses.

WILLIAM A. FEARN.
